Edward R. Knowles.

UNITED STATES PATENT OFFICE.

EDWARD R. KNOWLES, OF BROOKLYN, NEW YORK, ASSIGNOR OF ONE-HALF TO BYRON A. BROOKS, OF SAME PLACE.

STORAGE-BATTERY.

SPECIFICATION forming part of Letters Patent No. 291,850, dated January 8, 1884.

Application filed June 2, 1882. (No model.)

To all whom it may concern:

Be it known that I, EDWARD R. KNOWLES, residing in Brooklyn, in the county of Kings and State of New York, have invented certain new and useful Improvements in Storage-Batteries, of which the following is a description in such full, clear, concise and exact terms as to enable any one skilled in the art to which it appertains to make and use the same, reference being had to the accompanying drawings, making part of this specification, and to the figures and letters of reference marked thereon—

Figure 1 of said drawings being a perspective of said battery, partly in section; and Figs. 2, 3, and 4, detail parts of the same.

My invention consists of a novel method of constructing a storage-battery, the object of which is to secure a very powerful battery action.

My improved battery consists of two or more electrodes, each of which is composed of alternate plates or disks of lead and oxide of lead, or lead and sponge-lead, piled one upon the other, each electrode beginning and ending with a plate of metallic lead, and all of them being connected and combined into a battery.

In the drawings, Fig. 2 represents a top view and a vertical section of one of the electrodes, A, a number of which are combined in the battery illustrated by Fig. 1. In these electrodes, *a* is a disk of metallic lead, rectangular in form, and having a rectangular hole, *d*, in its center and a circular hole, *c*, in each of its ends. *b* is a disk, of precisely the same form, made of oxide of lead or sponge-lead. These disks are made into a pile, as shown, and held together by means of a lead rod passing through holes *c* and riveted at both ends, forming an electrode. Having made as many of these electrode-piles as I desire to incorporate into one battery, I take a suitable chamber or vessel, B, and fit it with a false bottom, C, of wood or any suitable material. In the false bottom I cut a series of holes to correspond in number and form to the electrodes the battery is to contain. Into the holes of this bottom the several electrodes are set, thus retaining the bottom of each electrode always in the same position. Now, to secure the top

of each electrode, I make a skeleton cover, *c'*, 50 precisely like the false bottom, and put it in the top of the chamber B, the top of each electrode being embraced by a corresponding mortise in the cover. The false bottom and the skeleton cover being both made to exactly 55 fit the chamber B, as well as each electrode, the whole is securely held in place. The electrodes being placed in the chamber, as described, I connect them electrically by the conductors E F E' E'' and the positive and negative poles D and D'. The chamber is then charged with acidulated water and closed with a tight cover to prevent evaporation.

By Fig. 3 of the drawings is shown a section and top view of an electrode-pile differing 65 from Fig. 2 in that the disks or plates have but one hole through the center, into which a lead bolt or rod is placed, riveted at both ends to hold the disks together.

By Fig. 4 of the drawings is shown a perspective of one of the disks composing the piles contained in the battery.

In constructing my battery I use in the formation of the positive electrodes alternate plates, buttons, or disks of lead and compressed sponge-lead; and in the formation of my negative electrodes alternate plates, buttons, or disks of lead and compressed oxide of lead, thereby making a pile-electrode and securing a very powerful battery action.

Having thus described my invention, I claim and desire to secure by Letters Patent—

1. In a storage-battery, the combination of positive electrodes composed of alternate plates of metallic lead and compressed sponge-lead, and negative electrodes composed of alternate plates of metallic lead and compressed oxide of lead, the said plates being mechanically united by means of rivets, substantially as described.

2. In a storage-battery, the combination of positive electrodes composed of alternate layers of metallic lead and compressed sponge-lead, and negative electrodes composed of alternate layers of metallic lead and compressed oxide of lead, all of which, both metals and oxides, are perforated, substantially as described, for the purpose specified.

3. In a storage-battery composed of compound electrodes, the combination of rivets *cc* with the alternate layers of metallic lead and compressed sponge-lead, forming one electrode 5 of the battery, and also with the alternate layers of metallic lead and compressed oxide of lead, forming the other electrode of the battery, substantially as described.
4. A storage-battery composed of compound 10 electrodes, the positive electrodes being composed of alternate layers of metallic lead and compressed sponge-lead, and the negative electrodes being composed of alternate layers of
- metallic lead and compressed oxide of lead, all being immersed in the electrolytic liquid, and 15 perforated, united, and electrically connected, substantially as described.
5. In a storage-battery consisting of a series of separate electrodes, the combination of a false bottom, *C*, and a cover, *C'*, each of which 20 is perforated to receive and support the electrodes, substantially as described.

EDWARD R. KNOWLES.
